CLAIM

(52) U.S. Cl. **D8/64; D8/61**

We claim the ornamental design for a handle arrangement for a reciprocating saw, as shown and described.

(58) Field of Search .... D8/61-70; 81/57.11, 81/469, 57.13, 54, 57.42, 474; 173/170, 217, 169, 164, 213, 216; 408/239 R, 124; 451/344, 295, 357-359; 310/50; 15/3.53; 30/392-394, 376

DESCRIPTION

(56) **References Cited**

FIG. 1 is a perspective view of a handle arrangement for a reciprocating saw showing our new design;

U.S. PATENT DOCUMENTS

FIG. 2 is a left side view thereof;

D. 323,274 * 1/1992 Sasaki et al. D8/61
 D. 376,083 * 12/1996 Verdura et al. D8/61
 D. 380,658 * 7/1997 Bruno et al. D8/61

FIG. 3 is a top view;

FIG. 4 is a right side view;

FIG. 5 is a bottom view;

FIG. 6 is a front view;

FIG. 7 is a rear view;

FIG. 8 is a perspective view showing our new design in an alternate position for use;

FIG. 9 is a left side view thereof;

FIG. 10 is a top view;

FIG. 11 is a right side view;

FIG. 12 is a bottom view;

FIG. 13 is a front view; and,

FIG. 14 is a rear side view thereof.

The power supply and portions of the reciprocating saw are shown in broken lines as same are for illustrative purposes only and form no part of the claimed design. The broken lines shown within the boundaries of the claimed surfaces are superimposed on continuous, uninterrupted surfaces and are for illustrative purposes only and form no part of the claimed design.
